CLAIM

The ornamental design for a sliding shower door, as shown and described.

DESCRIPTION

FIG. 1 is a front perspective view of a sliding shower door showing my new design, the sliding panels being closed;

FIG. 2 is a front perspective view thereof, the sliding panels being open;

FIG. 3 is a side elevational view thereof, the panels being closed;

FIG. 4 is a top plan view thereof, the panels being closed;

FIG. 5 is a top plan view thereof, the panels being open;

FIG. 6 is a rear elevational view thereof, the panels being closed;

FIG. 7 is a side elevational view thereof as seen from the interior;

FIG. 8 is a front elevational view thereof;

FIG. 9 is a front perspective view of a second embodiment of my new design, the panels being closed;

FIG. 10 is a front perspective view thereof, the panels being open;

FIG. 11 is a side elevational view thereof;

FIG. 12 is a top plan view thereof, the panels being closed;

FIG. 13 is a top plan view thereof, the panels being open;

FIG. 14 is a rear elevational view thereof;

FIG. 15 is a side elevational view thereof as seen from the interior; and

FIG. 16 is a front elevational view thereof.
